UNITED STATES PATENT OFFICE.

EDWIN NATHAN DENISON, OF WESTERLY, RHODE ISLAND.

DESIGN FOR A SPOON.

SPECIFICATION forming part of Design No. 22,859, dated October 31, 1893.

Application filed May 15, 1891. Serial No. 392,910. Term of patent 7 years.

To all whom it may concern:

Be it known that I, EDWIN NATHAN DENISON, a citizen of the United States, residing at Westerly, in the county of Washington and State of Rhode Island, have invented and produced a new and original Design for a Spoon or other Article, of which the following is a specification, reference being had to the accompanying drawing, forming a part thereof.

5 The drawing is a face view of a spoon having the handle stamped or otherwise produced with my ornamental design in relief.

10 This design is intended for souvenir spoons and similar articles.

15 The leading feature of the design consists in a handle on curved lines with a panel at

its larger end surrounded by scroll work and having in said panel an equestrian statue; beneath the said panel is a smaller panel, and the space between the last mentioned panel 20 and the bowl is occupied by a scroll and floral design upon an ornamental base.

What I claim is—

The design for a spoon, or similar article, as herein shown and described. 25

In testimony that I claim the invention above set forth I affix my signature in presence of two witnesses.

EDWIN NATHAN DENISON.
